E. C. WESTHOFF

DOOR SPRING,

APPLICATION FILED SEPT. 14, 1915.

1,186,720.

Patented June 13, 1916.

Fig. 1.

UNITED STATES PATENT OFFICE.

EDWARD C. WESTHOFF, OF BETHALTO, ILLINOIS.

DOOR-SPRING.

1,186,720.

Specification of Letters Patent. Patented June 13, 1916.

Application filed September 14, 1915. Serial No. 50,674.

To all whom it may concern:

Be it known that I, EDWARD C. WESTHOFF, a citizen of the United States, residing at Bethalto, in the county of Madison and State of Illinois, have invented certain new and useful Improvements in Door-Springs, of which the following is a specification.

This invention relates to an improved door spring and the principal object of the invention is to provide a spring which can be connected with the door frame and connected with the door by means of a line wound about a spring control drum, the unwinding of the line winding the spring so that when the door is released the spring will unwind and thus wind the line upon the drum and draw the door to a closed position.

Another object of the invention is to so construct the spring that the housing may be easily connected with the door frame and the spring and drum easily connected with the frame, the axle for the drum serving as the center pin for the spring.

Another object of the invention is to provide a closing device of the character described which will be very strong and durable and not liable to easily get out of order and which will be very inexpensive to manufacture and thus easy to construct and permitted of being placed upon the market at a relative small cost.

This invention is illustrated in the accompanying drawings, wherein:-

Figure 1 is a view showing a fragment of a door in elevation with the improved spring closer shown in position in elevation. Fig. 2 is a sectional view taken along the line 2-2 of Fig. 1. Fig. 3 is a sectional view taken along the line 3-3 of Fig. 1. Fig. 4 is a sectional view taken along the line 4-4 of Fig. 2.

The door 10 which in the illustration is a screen door is hingedly connected with the door frame 11 by means of hinges as shown at 12 and is normally held in the closed position by means of the improved device which forms the subject matter of this invention and is shown in position in Figs. 1, 2 and 3. With this improved device the door can be very easily opened and after

being opened will be drawn shut and held in the closed position thus preventing flies from entering the house through the doorway. The frame or body portion 13 of this device is formed from a sheet metal blank which is bent to provide the upper and lower leaves 14 and 15 between which the coil spring 16 is positioned with its outer end connected with the securing pin or bolt 17 and its inner end connected with the axle or pivot pin 18.

The drum 19 which carries the line 20 is rigidly mounted upon the axle or pivot pin 18 and after being coiled about the same as shown in Fig. 1 is extended so that a hook 21 may engage the eye 22 carried by the door 10. It will thus be seen that when the device is put in place as shown in Fig. 3 and secured to the door way by means of the screws 23 which may pass through the openings 13' and 14' the door will be held in the closed position. When the door is opened the line 20 is unwound from the drum thus turning the drum and axle and winding the spring. When the door is released the spring unwinds thus causing the line to be wound upon the drum and drawing the door closed. Of course the spring does not completely unwind and therefore the line will be held under tension sufficient to prevent the door from swinging outwardly after being closed.

It should be noted that this device is small and therefore will not take up much room and further being out of the way when put in place. It should be further noted that the parts of this device are very simple in construction and therefore are not liable to break or get out of order.

In order to prevent the spring from completely unwinding when the hook 21 is disconnected from the eye 22, a notch 23' has been provided to receive the hook.

What is claimed is:-

A door closer comprising a frame formed from a blank bent to provide the bridge and upper and lower leaves extending from said bridge, the lower leaf being provided with a cutout, a rotatable axle extending through said upper and lower leaves and beneath the lower leaf, a coil spring se-

cured between said leaves and having its inner end connected with said axle, a drum rigidly mounted upon said axle beneath said lower leaf, and a line connected with said drum and wound thereon and having its outer end portion provided with engaging means for connection with a door and for fitting into the cutout of the lower leaf to

hold the line wound upon the drum with the spring under tension.

In testimony whereof I affix my signature in presence of two witnesses.

EDWARD C. WESTHOFF.
